UNITED STATES PATENT OFFICE.

JAMES M. KELLY, OF CHICAGO, ILLINOIS.

EXTENSION-STEP.

1,146,429.

Specification of Letters Patent. Patented July 13, 1915.

Application filed April 25, 1914. Serial No. 834,453.

To all whom it may concern:

Be it known that I, JAMES M. KELLY, a citizen of the United States, residing at Chicago, in the county of Cook and State of Illinois, have invented certain new and useful Improvements in Extension-Steps, of which the following is a specification.

The object of my invention is to provide a step of this type for use on electric or railroad coaches or in other connections where grade stops are necessary, so constructed and arranged that at least one step of the steps can be folded up to a position beneath the remaining steps when not in use, and when in use is extended outwardly and downwardly to bring a person into closer proximity to the ground when alighting from the step.

A further object is to so construct the parts, comprising steps located in a well formed in the floor of the vehicle and the well provided with the usual door, that when the door is opened the extension steps are swung down into position and when the door is closed the extension steps are folded up and beneath the remaining or stationary step.

Yet another object is to so construct the parts that when the door covering the stationary step is closed no part of the steps projects beyond the side of the car.

With other objects in view, which will be referred to, my invention consists in the peculiar combination and novel arrangement of the parts such as will be hereinafter more fully described in connection with the accompanying drawings and more particularly pointed out in the appended claims.

In the drawings:—Figure 1 is a view diagrammatically illustrating in end elevation a car with parts in section to show the manner of applying my invention thereto. Fig. 2 is a view in side elevation of the car. Fig. 3 is a fragmentary sectional view on the line 3—3 of Fig. 1. Fig. 4 is a fragmentary sectional view similar to the disclosure in Fig. 1 but showing the parts in changed relative positions. Fig. 5 is a vertical sectional view on the line 5—5 of Fig. 1.

The car 1 has the usual well or opening 2 provided through the floor 3 thereof, and a set of stationary steps 4 are mounted within this well or opening. A door 5 is hinged at 6 adjacent the well 2 to close down over the opening through the floor of the car and make

this floor 3 substantially continuous when it is not desired to use the step. The steps 4 are built up in the usual manner to comprise tread and risers and the brackets 7 are secured to the under side of the lowermost tread 8. A plate 9 is pivoted near the forward end of the tread 8 between brackets 7 on a rod 10 to form a riser of the extensible step, and the tread plate 11 is hinged to the riser plate 9 by a rod 12. The plates 9 and 11 at their hinged joints are so arranged that the riser plate 9 can be swung up against the under side of the tread 8 of the lowermost stationary step and the tread plate 11 of the extensible step can be swung up flat 70 against the riser plate 9. A bracket 13 is secured to the under side of the tread of the step 14 in the upper part of the stationary step 4, and a bell crank lever 15 is pivoted at its angle to this bracket. A bracket 16 is secured to the riser of the step 14 and an operating lever 17 is pivoted in its body portion to this bracket, a link 18 pivoted to one end of the operating lever 17 and to an arm of the bell-crank lever 15 being provided to 80 form a flexible connection between these two members. An arm 19 is rigidly secured at its one end to the under side of the tread 11 of the extensible step and at its free end is pivotally connected at 26 to the free end of 85 the bell-crank lever 15. An arm 20 is secured to the under side of the door 5 adjacent the hinge connection 6 with the floor and extends down through the floor through an opening 21 approximately at right angles 90 to the longitudinal extent of the door. This arm 20 has a bearing pin 22 formed on the free end thereof and this bearing pin extends through a slot 23 formed in the free end of the operating lever 17. Through the 95 arrangement as above described, a complete chain of connecting parts is provided through arm 20, operating lever 17, link 18, bell-crank lever 15 and arm 19 from the door 5 to the tread 11 of the extension steps. 100

It will of course be understood that a door-opening 24 is provided through the side of a car adjacent the point at which the steps 4 are located, and a car door 25 is provided to close the door-opening 24 when the door 5 is in a lowered or closed position.

The use and operation are as follows. The car door 25 is swung from the car door opening 24 and this permits the floor door 5 to be raised to a position shown in Figs. 110

1, 3 and 5, so that the well 2 through the floor of the car is opened. The arm 20 secured to the door 5 through its connection in the slot 23 of the operating lever 17 causes this lever to be swung about its pivot on the bracket 16 and to the connection of the link 18 to transmit a swinging movement to the bell-crank lever 15. As the bell-crank lever 15 is shifted, the extension step is, through the connection of the arm 19 rigidly secured to the tread 11 with an arm of the bell-crank lever 15, swung to its extended or operative position, this operative position being perhaps better shown in Fig. 15. As the door 5 in its open position is swung upwardly and then secured against closing again, and the arms 19 and 20 are rigidly secured to the parts with which they are connected, the tread 11 of the extension step will be held rigidly in its extended position, but when the door 5 is again closed the parts operate in a reverse relation than that described, the operating lever 17 is swung to one side and through its connection by link 18 with the bell-crank lever 15 to swing this bell-crank lever about its pivotal connection on bracket 13. The connection of the arm 19 at 26 with the arm of the bell-crank lever 15 causes the tread and riser of the extension step to be swung into the position shown in Fig. 4 where they lie beneath and against the tread 8 of the stationary step.

From the foregoing, it will be seen that I have provided a device of the character described, simple and inexpensive to manufacture and install yet efficient in operation, and one which may be installed in the vehicle either at the time of the manufacture or after the vehicle has left the factory.

While I have herein shown and described one specific form of my invention, it will be understood that slight changes might be made in the form and arrangement of the parts without departing from the spirit and scope of my invention, and hence I do not wish to be limited thereto except for such limitations as the claims may import.

I claim:—

50. 1. In a vehicle having an opening through the floor thereof, a door hinged adjacent thereto to swing down over and close said opening, a set of steps mounted within the opening, at least one of said steps having the tread and riser thereof pivoted together and hinged to the tread of the steps above in such a manner that these members may be collapsed to a position to rest one beneath the other and against the under side of the tread of the step above, an arm secured to the door to swing therewith, and a bell-crank lever connected between said arms and said folding steps in such a manner that as the door is closed the bell-crank lever is given swinging movement about its point

of mounting and the step is brought to its collapsed position and as the door is opened the step is moved to its extended position.

2. In a vehicle having an opening through the floor thereof, a door hinged adjacent thereto to swing down over and close said opening, a set of steps connected in the opening, at least one of said steps constructed to be collapsed and folded up under the remaining step, a bell-crank lever pivotally connected with one of the non-folding steps, and means connected between the bell-crank lever and the door and between the step and the bell-crank lever in such a manner that as the door is opened the step is brought to its extended position and as the door is closed the step is brought to its collapsed position.

3. In a vehicle having an opening through the floor thereof, a door hinged adjacent thereto to swing down over and close said opening, a set of steps mounted within the opening, at least one of said steps having the tread and riser thereof hinged together and hinged to the tread of the step above in such a manner that they may be collapsed to rest beneath and against the under side of the tread of the step above, an arm secured to the door to swing therewith, an arm rigidly connected with the tread of the collapsible step, a bell-crank lever pivoted to one of the stationary steps, and said arms and the bell-crank lever so connected that as the door is swung to its open position the step is brought to an extended relation and as the door is closed the step is swung to its collapsed position.

4. In a vehicle having an opening through the floor thereof, a door hinged adjacent thereto to swing down over and close said opening, a set of steps mounted within the opening, at least one of said steps having the tread and riser thereof hinged together and hinged to the tread of the step above in such a manner that the riser and tread may be collapsed to rest beneath and against the underside of the tread of the step to which the same is hinged, an arm rigidly connected with said door to extend substantially at right angles thereto, an arm rigidly connected with the tread of the collapsible step, a bell-crank lever pivoted at its angle bearing to one of the stationary steps, the arm from the step tread connected with one of the swinging arms of said bell-crank lever, a lever pivoted to one of said stationary steps and connected with the free arm of the bell-crank lever, and a connection between said swinging lever and the arm rigidly mounted on the door so formed that as the door is swung to the open position the step is extended and as the door is closed the step is withdrawn to the folded relation.

5. In a vehicle having an opening through the floor thereof, a door hinged adjacent

thereto to swing down over and close said opening, a set of steps mounted within the opening, at least one of said steps having the tread and riser thereof hinged together 5 and to one of the stationary steps in such a manner that the riser and tread may be collapsed to a folded relation, an arm rigidly secured to the door to extend substantially at right angles thereto, a bell-crank lever pivoted 10 at its angle bearing to the structure of the stationary steps, an arm rigidly secured to the tread of said collapsible step and pivotally connected with one of the arms of the bell-crank lever, a swinging lever pivoted to 15 the riser of one of the steps and connected with the free arm of the bell-crank lever,

said swinging lever provided with a slot through the free end thereof, and a projection from the arm secured to the door adapted to be received through the slot of 20 this swinging lever and to mount the parts in such relation that as the door is brought to the open position the step is extended and upon closing of the door the step is contracted to its folded relation. 25

In testimony whereof I affix my signature in presence of two witnesses.

JAMES M. KELLY.
